CORK INSERT GIRT

Alpheus O. Hurxthal, Philadelphia, Pa., assignor
to Proctor & Schwartz, Incorporated, Philadelphia, Pa., a corporation of Pennsylvania

Application July 12, 1935, Serial No. 31,127

10 Claims. (Cl. 34—20)

This invention relates to girts for conveyers used, for example, in drying apparatus, for cloth and other web or sheet material, such as disclosed in the applicant's prior Patent No. 1,996,020 dated 5 March 26, 1935 and in other forms of loop driers, etc.

The present invention relates particularly to a girt having a material-engaging face composed of cork or similar or equivalent material having a low 10 heat conductivity, and has for its object the provision of a girt which will reduce to a minimum or eliminate entirely marking of the goods at the places where the goods is engaged by the supporting conveyer as it passes through the drying apparatus.

Another object of the invention is to make the girts as a whole independently removable from the side chains of the conveyer and to make the facing material in a form which will be interchangeable and readily replaceable in order that a worn 20 or damaged facing on any of the girts of the conveyer may be readily replaced.

Another object of the invention is to make the facing material and the girt body in such form as will permit the facing material to be reversed to 25 present a new surface for engagement with the goods at such time as the one surface becomes worn, soiled or otherwise damaged in the course of usage.

The construction of the girt and the conveyer will be more fully described hereinafter, reference 30 being had to the accompanying drawing, of which:

Fig. 1 is a fragmentary plan view of the conveyer with one of the girts made according to the principles of the present invention in place 35 thereon;

Fig. 2 is a sectional elevation taken longitudinally of the girt on the line 2—2, Fig. 1;

Fig. 3 is a detached fragmentary perspective view, partly in section, of one end of the girt and the adjacent side chain shown in Figs. 1 and 2;

Fig. 4 is an enlarged transverse sectional elevation of the girt taken on the line 4—4, Fig. 2;

Fig. 5 is a transverse sectional elevation taken 45 on the line 5—5, Fig. 2;

Fig. 6 is a view similar to Fig. 4 but showing a modified form of the invention; and

Figs. 7 and 8 respectively illustrate other modified forms of the girt.

As shown in Figs. 1 to 4, the preferred form of the invention comprises a metallic girt body A of substantially channel-shaped cross-section including a base or web 1, from which extend parallel side flanges 2, 2. At the upper ends of the side flanges 2, 2 are inturned top flanges 3, 3 which extend substantially parallel to each other and to the base web 1, longitudinally of the girt, in vertically spaced relation to the base web 1.

In each of the opposite ends of the channel girt

is a fitting 5 (see Fig. 5) of a generally U-shaped construction including a bar 6, which is adapted to be secured to the base web 1 of the girt by a bolt 7; a pair of vertical legs 8, 8 which project upwardly between the inner edges of the inturned flanges 3, 3 of the girt; a pair of outwardly projecting arms 9, 9 which rest on top of the inturned flanges 3, 3 respectively and which are connected to reversed or inturned arms 10, 10 respectively by curved portions 11, 11 to provide bearing openings or recesses 12, 12 for the reception of supporting studs 13, 13 extending inwardly of the conveyer from the side chains 15, 15 thereof respectively.

As shown in Figs. 1, 2 and 3, the studs 13, 13 15 constitute elongated extensions of the pintle pins which connect the links 14, 14 of the side chains 15 together and provide bearings for the conveyer rollers 17, 17 of the conveyer. Obviously, the studs 13, 13 may be independent of the chain pintles and 20 extend from the links 14, 14 intermediate the ends thereof.

The upper face of the girt, as formed by the inturned flanges 3, 3, is adapted to receive the facing of cork or other heat-resisting material of low 25 conductivity and in the preferred form of the invention the cork is made into an elongated strip 20 in one piece or as a series of shorter sections placed end to end. In that form of the invention shown in Figs. 1 to 4, the cork strip 20 is substantially rectangular in cross-section and presents 30 two parallel though oppositely disposed material-engaging surfaces 21, 21, which preferably are flat but which may be arched transversely if desired.

The side edges 22, 22 of the rectangular strip 20 are provided with longitudinal grooves 23, 23, disposed in a plane substantially midway between the planes of the surfaces 21, 21 of the strip, which are adapted to receive the inturned flanges 3, 3 of the body portion of the girt to support the bearing strip 20 thereon without any additional securing means and in such a manner that either 35 of the surfaces 21, 21 may be presented to the goods to be carried by the girts of the conveyer.

In order to prevent the material from shifting transversely of the conveyer outwardly over the side chains 15 each or any desired number of the girts are provided with end brackets 24, 24 having one leg 25 extending vertically at the ends of the strip 20 to a position above the plane 40 of the bearing surface 21 of the strip 20 and a leg 26 disposed on top of the base 6 of the U-shaped bearing fitting 5 and secured in place thereon by the bolt 7. The vertical legs 25 engage the opposite ends of the strip 20 and insure against 45 any relative longitudinal shifting between the strip 20 and the body of the girt. This is of value particularly when and if the strip 20 is composed of a series of sections set end to end on the flanges 3, 3 to prevent the formation of 50

crevices in the material-engaging surface of the girt into which the goods might pass and be pinched.

In that form of the invention shown in Figs. 1 to 4, the width of the strip 20 is substantially equal to the distance between the inner faces 27, 27 of the vertical flanges or legs 22 of the girt body and the active face 21 of the strip is disposed at such an elevation above the top plane 10 of the flanges 3, 3 as to prevent the goods from engaging the metal portions of the girt when the goods suspended between the surfaces 21, 21 of successively adjacent girts bellies, sags or is depressed between the girts as in the apparatus 15 disclosed in the above noted prior patent.

If desired, to insure against the material from engaging the metallic part of the girt when the chains are ascending and/or descending the sides of the undulations of the conveyer path as shown 20 in said prior patent, one or both sides of one of the faces 21 may be extended beyond the vertical plane of the side flanges 2, 2 of the girt body, as shown at 22a in Fig. 6, or the side walls may be made convergent as shown at 2a, 2 in Fig. 7, 25 or the girt may be tubular as shown at 28 in Fig. 8 with the facing material made in the form of a tubular sleeve 30 to enclose the metallic tubular rod or girt 28.

In the case of a girt made tubular as in Fig. 8, 30 the ends of the tube 28 may be made to revolve on or to be adjustably fixed to oppositely disposed axially aligned studs 13, 13 of the side chains 15, 15 to present different bearing surfaces to the goods when desired.

From the above, it will be clear that in case 35 the metallic girt is faced with a material of low heat conductivity to prevent the material from engaging the hot metallic portion of the girt which with some materials such as rayon and natural thread silk will cause the formation of 40 marks on the goods as it is transported through the drying chamber on the supporting conveyer.

Another advantage attending the use of cork in addition to its low heat conductivity qualities is 45 its tendency to hold the material against slipping as the conveyer ascends and descends the opposite sides of the undulations of the conveyer course as disclosed in the above noted prior patent.

I claim:

1. A girt for web drier conveyers comprising a metallic body and a body of cork partially enclosed by and projecting outwardly beyond said metallic body, said projection affording a goods 55 engaging surface on the girt.

2. A girt for web drier conveyers comprising a channel-shaped metallic body and a cork strip located in the open side of said body and projecting above the side edges of the channel for affording a goods engaging surface on the girt.

3. A girt for web drier conveyers comprising a channel-shaped metallic body including an open side provided with opposed inturned flanges, and a cork strip located in the open side of said body and having opposed side grooves for receiving said flanges and a goods engaging surface disposed in a plane spaced from that of said 65 grooves and from said metallic body.

4. A girt for web drier conveyers comprising a channel-shaped metallic body including an open side provided with opposed inturned flanges, and a reversible cork strip located in the open side of said body and having opposed side 70 grooves for receiving said flanges and a pair of

opposed goods engaging surfaces respectively disposed in planes above and below and in spaced relation to the plane of said grooves and adapted to be reversed to position either of said surfaces outwardly beyond said metallic body. 5

5. A girt for web drier conveyers comprising a metallic body including a base and side flanges extending from opposite edges thereof and an open side opposite said base, opposed inturned flanges on said side flanges, and a cork strip disposed in the open side of the channel between said side flanges and provided with side grooves for respectively receiving said inturned flanges and supporting said strip with one face in spaced relation to said base and an opposite face affording a goods engaging surface in a plane disposed above and beyond the tops of said side flanges and said plane of said inturned flanges. 10

6. A girt for web drier conveyers comprising a metallic body, a cork facing for and projecting from said body, a supporting bearing at each end of said body and arranged with its axis substantially parallel to the longitudinal axis of the girt, a pair of laterally spaced chains, studs on said chains and projecting laterally therefrom 15 into said bearings, and means for removably securing said bearings to said body.

7. A girt for web drier conveyers comprising a metallic body, a cork facing for and removably mounted on and projecting from said body, a 20 supporting bearing at each end of said body and arranged with its axis extending substantially parallel to the longitudinal axis of said girt, a pair of laterally spaced chains, studs on said chains and projecting laterally therefrom 25 into said bearings, and means for removably securing said bearings to said body.

8. A girt for web drier conveyers comprising a metallic body, a reversible cork strip removably mounted on and projecting from said body, a 40 supporting bearing at each end of said body and arranged with its axis extending substantially parallel to the longitudinal axis of said girt, a pair of laterally spaced chains, studs on said chains and projecting laterally therefrom 45 into said bearings, and means for removably securing said bearings to said body.

9. A girt for web drier conveyers comprising a metallic body including a pair of opposed flanges, a reversible cork strip mounted between 50 and having side grooves for receiving said flanges, supporting bearings at opposite ends of said body and arranged with their axes substantially parallel with the longitudinal axis of said girt, a pair of laterally spaced side chains, studs on the side 55 chains and projecting into the supporting bearings respectively, and means for removably securing the bearing to the body.

10. A girt for web drier conveyers comprising a metallic body including a pair of opposed 60 flanges, a reversible cork strip loosely mounted between and having side grooves for receiving said flanges, abutments at the opposite ends of said girt for preventing relative longitudinal movement between the strip and the body, supporting bearings at opposite ends of said body and arranged with their axes substantially parallel to the longitudinal axis of said girt, a pair 65 of laterally spaced side chains, studs on the side chains and projecting laterally therefrom into the supporting bearings respectively, and means for removably securing the bearings and said movement-preventing abutments to the body.

ALPHEUS O. HURXTHAL.
